UNITED STATES PATENT OFFICE.

JAMES S. PATTEN, OF BALTIMORE, MARYLAND, ASSIGNOR TO THE BALTIMORE JOURNAL BOX COMPANY, OF BALTIMORE, MARYLAND, A CORPORATION OF MARYLAND.

JOURNAL BOX AND LID.

No. 831,466.

Specification of Letters Patent.

Patented Sept. 18, 1906.

Application filed June 5, 1905. Serial No. 263,799.

To all whom it may concern:

Be it known that I, JAMES S. PATTEN, a citizen of the United States, residing at Baltimore, State of Maryland, have invented 5 certain new and useful Improvements in Journal Boxes and Lids; and I do hereby declare the following to be a full, clear, and exact description of the invention, such as will enable others skilled in the art to which 10 it appertains to make and use the same.

This invention relates to journal-boxes such as are employed on railway-cars, and more particularly to the lids of the boxes and the portions of the boxes directly coöperating therewith, such as illustrated in my 15 pending application filed April 4, 1905, and bearing the Serial No. 253,830.

The object of the present invention is to provide an arrangement of spring which will 20 serve not only to hold the lid yieldably in closed position, but also to hold it at the upper limit of its movement, so as to insure a dust-proof closure at the upper edge of the box.

25 Other objects and advantages of the invention have reference to details of structure, as will be understood from the following description.

In the drawings forming a portion of this 30 specification and in which like numerals of reference indicate similar parts in the several views, Figure 1 is a vertical section through a portion of a journal box and lid embodying the present invention, parts of the structure 35 being in elevation. Fig. 2 is a view similar to Fig. 1 illustrating the modified form of pull-rod. Fig. 3 is a view similar to Fig. 1 showing a lifting-spring of such shape and arrangement as to obviate the necessity for 40 the pull-rod. Figs. 4 and 5 are views similar to Fig. 3 showing the employment of plate-springs for raising and holding the lid in raised position. Figs. 6, 7, 8, 9, and 10 are 45 detail sectional views of portions of the faces of boxes and the portions of the lids resting thereagainst at the sides of the end opening of the box.

Referring now to the drawings, and more 50 particularly to Fig. 1 thereof, there is shown a portion of the journal-box 20, in the outer end of which is the usual opening to permit of application of waste and lubricant. From the top of the box and overhanging the front

opening of the latter there projects upwardly and forwardly a lug 22, which is embraced by 55 the ears 23, that project upwardly from the lid 24. The upper portion of the box at the base of the ear 23 likewise overhangs the end opening of the box, as shown at 25, and in the under face of this overhanging portion is 60 formed a recess that extends transversely of and throughout the width of the box. The rear wall 26 of this recess is flat and is in the same plane with the face 27 of the box at the sides of the end opening, so that the lid 24 65 may fit with its upper portion snugly against the face 26 when in closed position. The upper face 28 of the recess is curved and is concentric with the pivot-pin 29, that connects the ears 23 with the ear 22, and the upper end 70 of the lid 24 is beveled on a curve to correspond to the face 28, so that when the lid 24 is in closed position and lying snugly against the face 26 its upper concaved face will 75 snugly receive the convex face 28. To prevent excessive wear of the face 28 against the lid, a stop-flange 30 is formed upon the inner face of the lid in position to strike the bottom face of the top of the box when the lid is in closed position. It will be noted that the 80 perforation 31 in the ear 22, that receives the pin 29, is elongated, so that the pin may have substantially vertical movement or a movement in a direction to permit of the lid being raised as it springs into closed position. To 85 swing the lid into closed position and at the same time to raise it and also to hold it yieldably in closed position, a pull-rod 32 is provided, the upper end portion of which is in hook form and is pivoted to an ear 33 or a 90 lug that extends upwardly and rearwardly from the ear 22. The hook embraces the ear 22 and below the hooked portion the rod passes through a lug 34 on the outer face of the lid 24, and through which lug it is 95 slideable. At the lower end of the rod 32 is a head 35, and between the head and the lug 34 is a helical spring 36, which by bearing against the head and lug serves to force the lid upwardly. Furthermore, the pivot 37 of 100 the rod 32 being to the rear of the pivot 29 of the lid the spring 36 tends to swing the lid to closed position, excepting when the headed end of the rod 32 is swung outwardly beyond a line passing through the centers of the 105 pivots 29 and 37, when the tendency of the

spring is to hold the lid in open position. The outer edge portion of the face 28 is more sharply rounded, as shown at 40, so that when the lid is swung into closed position its 5 upper edge may strike this face 40 and pass over it to the recess. As the lid swings into closed position the spring 36 serves to raise the lid, so that a close and dustproof contact is made between the curved faces of the 10 recess and lid.

Referring now to Fig. 2 of the drawings, there is shown a journal-box 20', having the overhanging portion 21' with the recess in its under face, the rear face 26' of which recess is 15 straight, while its upper face 27' curves in the same manner as in the structure above described. The box furthermore has an upwardly and forwardly projecting ear 22', which is embraced by the ears 23', that project from the outer face of the lid 24', and upon the outer face of said lid is also a lug 34', while a pivot-pin 29' is passed through the ears 23' and 22'. From the face of the 20 ear 22' below the pin 29' project laterally- 25 spaced ears 33', between which is pivoted on a pin 37' a pull-rod 32', which is passed downwardly and through a perforation in the lug 34', and has a head 35' at its lower extremity. Upon the rod 32' is disposed a helical spring 30 36', that bears against the lug 34' and the head 35' and tends to lift the lid 24' and hold it with its upper portion snugly against the faces 26' and 27', it being noted that the upper portion of the lid 24' is thickened and 35 shaped to fit the recess snugly when the box is in closed position. Upon the inner face of the lid 24' is a flange 30', that strikes the roof of the box when the lid is in closed position and prevents excessive wear of the face 27' 40 and the corresponding face of the lid.

With the construction illustrated in Fig. 2 it will be seen that with the parts in the positions shown the spring tends to force the lid against the box in an upward direction and 45 that this tendency is continuous while the lid is swung into open position until the lid moves so far as to carry the perforation of the lug 34' above the ear 22' and beyond a line passing through the centers of the pivots 50 29' and 37', after which the tendency of the spring is to move the lid over onto the top of the box, which action, however, is prevented by the overlying parts of the truck in use, with the result that the lid is held at a slight 55 inclination rearwardly. It will be understood, of course, that the position of the pivot 37' may be shifted to cause the spring to hold the lid at any desired angle. Referring now to Fig. 3 of the drawings, there is shown a 60 structure embodying a box 20'', to which is hinged a lid 24'' through the medium of ears 22'' and 23'' and pin 29'', all corresponding in construction and arrangement to the structure illustrated in Figs. 1 and 2, with the exception that the ear 22'' has a passage 23''

therethrough beneath the pin 29'', and in this passage is pivoted a bowed spring-plate 36'', the lower end of which is held between the front face of the lid 24'' and the cleat 34'' carried thereby. When the spring is engaged beneath the cleat, it is flattened and as the tendency of the spring is to bow and assume the position illustrated in dotted lines it tends to raise the lid and holds its upper portion snugly yieldably, as illustrated. 75

In the construction illustrated in Fig. 4 the parts are the same as illustrated in Fig. 3, with the exception that the lid 24'' is provided with a lug 34'', having the slanting lower face 50, against which bears the hooked end 51 of a spring-plate 36'', the upper end of which is pivoted in the passage 33'' in the ear 22''. The spring-plate 36'' passes loosely beneath the cleat 35''. The spring-plate 36'', when in the position illustrated, tends to slide 85 with its hooked end 61 downwardly or along the slanting or beveled face 50 of the lug 34'' and this action of the spring forces the lid upwardly and causes its upper end portion to fit snugly in the recess in the overhanging 90 portion of the box. The lower portion of the lid has a lip 52, projecting at an obtuse angle to the lid and which by contact with the bottom face 53 of the opening of the box not only aids in moving the lid upwardly, but 95 supports it.

The construction illustrated in Fig. 5 is the same as that illustrated in Fig. 3 with the exception that the cleat 34'' is in the angle between the outer face of the lid 24'' and the lip 100 52'', so that when the bowed spring-plate 36'' is forced beneath the cleat its extremity strikes the lip and is directed by it outwardly beneath the cleat into hook form to prevent withdrawal of the spring-plate. 105

It will be noted that in each of the constructions illustrated the pivot-pin connecting the lid with the box fits the ears of the lid loosely, so that a degree of vertical movement of the lid is permitted, so that the upper edge of the 110 lid will fit the recess in the box with proper snugness.

In use the lid has a slight movement with respect to the box, and in order that this movement may be taken advantage of to 115 grind the side and bottom edges of the opening of the box and the contacting portions of the lid the inner face of the lid may be caved, as illustrated in Fig. 6 of the drawings, to receive the broadened edge portion 60 of 120 the box, and may have a rib 61 bearing against said broadened edge, the side portions of the broadened edge being tapered, as illustrated, and making contact with the arched face of the lid. These sharp edges or 125 ridges will have initial rapid wear, so that any defects in casting that will preclude a dust-proof joint will be overcome.

In Fig. 7 of the drawings the edge portions 62 of the box are channeled to present sharp 130

ribs or ridges 63 and 64, which bear against the faces of channels 65 and 66, formed in the face of the lid, the lid having a ridge 67 that enters but does not fit the channel in the edge portion 62 of the journal-box.

5 In Fig. 8 of the drawings the edge portion 62' is the same as that illustrated in Fig. 7, the sharp ribs or ridges 63' and 64' bearing against face of recessed portions of the lid 70, while the ridge 67' is cut off flat to present two edges to the walls of the channel 68'.

10 In Fig. 9 of the drawings the edge portions 71 of the box are beveled and concaved to present the sharp edges 72, 73, and 74, the 15 central edge or rib 73 engaging the bottom of the channel 75 in the lid 76, while the edges 72 and 74 bear against the sides of the said channel.

15 In Fig. 10 of the drawings the lid 76' has a channel 75', and the edge portion 71' of the 20 box has a forwardly-directed rib 73' and laterally-directed ribs 72' and 74', the rib 73' engaging the bottom of the recess or channel 75, while the ribs 72' and 74' contact with the 25 side walls of said channel.

What is claimed is—

1. The combination with a journal-box having an opening therein and an adjacent recess above the opening, of a lid for said 30 opening hinged to the box and movable into engagement with said recess when in closed position and a spring arranged to swing the lid into closed position and simultaneously raise it.

35 2. The combination with a journal-box, of a lid connected thereto, the box having a portion disposed to overhang the upper portion of the lid when the latter is in closed position,

the connection of the lid with the box being such as to permit of bodily movement of the 40 lid toward and away from the overhanging portion of the box, and means arranged to swing the lid into closed position and simultaneously raise it bodily against said overhanging portion of the box.

45 3. The combination with a journal-box having a portion overhanging its end opening, of a lid for said opening hinged to the box and having bodily upward movement at the latter portion of its pivotal movement into 50 closed position to lie with its upper edge against said overhanging portion, and connections between the lid and the box comprising a spring and plunger arranged to swing the lid pivotally and upwardly into 55 closed position and against the overhanging portion.

4. The combination with a journal-box having an end opening and a cut-under portion overhanging said opening, of a lid for 60 said opening hinged to the box and movable upwardly and downwardly into and out of engagement with the overhanging portion, a rod pivoted to the box and having sliding connection with the lid, and a spring coöperating with the lid and rod and arranged to swing the lid pivotally and slide it upwardly along the rod against the overhanging portion of the box.

65 In testimony whereof I affix my signature 70 in presence of two witnesses.

JAMES S. PATTEN.
